DESIGN FOR A RUBBER HEEL.

SPECIFICATION forming part of Design No. 30,641, dated April 25, 1899.

Application filed March 28, 1899. Serial No. 710,829. Term of patent 14 years.

To all whom it may concern:

Be it known that I, HEBER C. PETERS, a citizen of the United States, residing at Boston, in the county of Suffolk and State of Massachusetts, have invented and produced a new and original Design for Rubber Heels, of which the following is a specification, reference being had therein to the accompanying drawings.

Figure 1 of the said drawings is a plan view of a heel, showing my new design. Fig. 2 is a sectional view taken on the dotted line 2 2 of Fig. 1.

As shown in the drawings, the leading or

material feature of my design consists of the 15 circular field of corrugations 1 2 at the middle of the wearing-face of the heel.

Having described my invention, what I claim as new, and desire to secure by Letters Patent, is—

The design for a rubber heel, as herein shown and described.

In testimony whereof I affix my signature in presence of two witnesses.

HEBER C. PETERS.
